UNITED STATES PATENT OFFICE.

ONESIME DANDURAND, OF MONTREAL, QUEBEC, CANADA, ASSIGNOR OF ONE-HALF TO
ERNEST CLAUDE GOUGH, OF MONTREAL, QUEBEC, CANADA.

OIL BURNER.

Application filed October 10, 1923. Serial No. 667,607.

To all whom it may concern:

Be it known that I, ONESIME DANDURAND, a subject of the King of Great Britain, and residing at the city of Montreal, in the 5 Province of Quebec, in the Dominion of Canada, have invented a new and useful Oil Burner, of which the following is the specification.

The invention relates to oil burners as described in the present specification and illustrated in the accompanying drawings that form part of the same.

The invention consists essentially of the novel features of construction pointed out 15 broadly and specifically in the claims for novelty following a description containing an explanation in detail of an acceptable form of the invention.

The objects of the invention are to facilitate the burning of oil in heating and other plants; to economize in the consumption of fuel particularly in dwellings and public buildings; to eliminate the use of auxiliary suction devices in such plants; to furnish 25 the burners at reasonable price well within the reach of all consumers and avoid coagulation of the fluid and consequent blocking of the ports; and generally to provide in an oil burning system low cost in regard to 30 production, efficiency in operation, durability in the machine, and simplicity in respect to maintenance.

In the drawings Figure 1 is a plan view of the parts to the system.

35 Figure 2 is an elevation of the burner from one end.

Figure 3 is an elevation from the other end.

40 Figure 4 is a side elevation of the several elements.

Figure 5 is a longitudinal sectional view on the line 5—5 of Figure 1.

Like numerals of reference indicate corresponding parts in the various figures.

45 Referring to the drawings, the primary burners 1 and 2 are preferably in parallel arrangement and suitably spaced, each having a plurality of jet orifices, here shown as 3, 4 and 6 and 7, 8 and 9 in central longitudinal rows, though they may be in lesser or greater numbers according to the capacity of the installation and also having the jets 10 and 11 respectively at the inner sides of the aforesaid rows.

55 The secondary burner 12 is also shown as

parallel to the primary burners 1 and 2 and therebetween, though at a much lower level and having a plurality of jet orifices 13 in much greater numbers than the primary burners and in longitudinal rows. 60

The primary burners 1 and 2 at one end are connected by the pipe 14 and this pipe is connected to the oil supply tank 15 by the pipe 16 having the shut off valve 17, the tank 15 preferably contains crude oil. 65 The other ends of said burners 1 and 2 are connected by the pipe 18, the steam gland 19 being introduced in said connection 18.

The pipe 18 is connected to the secondary burner 12 by the pipe 20, so that the oil 70 entering the burners 1 and 2 exudes a vapor which is consumed from the jets and the oil and unconsumed vapor flows on to the secondary burner 12 and is finally and fully vaporized and consumed at the jets 13. 75

The gas consumed is of course not only the vapor from the oil, but is a hydro carbon gas, as steam is generated in the stand pipe form of casing 21 which is connected to a water tank 22 by the pipe 23 having a shut off valve 24 and from said tank 22 the system is supplied with one half gallon of water to every gallon of oil, or thereabouts. The steam generator casing 21 is connected to the steam chest 25 by the pipe 26, the steam 85 being superheated in this chest, and flowing on through the pipes 27 and 28 to the burners 1 and 2, the additional gland 29 being provided in the pipe 28.

It will thus be seen that the expansion of 90 the steam in the chest 25 will cause it to flow at considerable velocity into the burners, where it mixes with the vaporized oil and carries the oil particles with it through the several jets, where combustion takes place 95 due to the first ignition. A pan 30 may be provided for a preliminary heating or any other suitable means and any inflammable material is burned in the pan.

What I claim is:—

1. In an oil burner, a primary steam cylinder connected from one end to a water supply, a superheating steam chamber connected to the other end of said cylinder, primary oil burners having jet orifices, and connected from one end to an oil supply and to the ends of said superheating chamber and a secondary oil burner connected to the other ends of said primary oil burners and having a greater number of jet orifices. 110

2. An oil burning system, comprising a pair of cylindrical casings suitably spaced and having a longitudinal row of jet orifices and jet orifices staggered from said longitudinal row, a cylindrical burner central in relation to the aforesaid burners and at a lower level and having longitudinal rows of jet orifices, pipe connection from one member of said pair to the other and from said connection to the lower burner, a standpipe steam generator casing, a steam chest con-

nected to said generator, pipe connections from said chest to said pair of burners, an oil tank, a water tank, pipe connections to said pair of burners from said oil tank having a shut off valve therein and pipe connections to said generator from said water tank having a shut off valve therein. 15

Signed at Montreal, Canada, this 17th day of September, 1923.

ONESIME DANDURAND.
